(57) **CLAIM**

The ornamental design for a steam generating canister, as shown.

DESCRIPTION

FIG. 1 is a front perspective view of a steam generating canister showing my new design;

FIG. 2 is a top plan view thereof;

FIG. 3 is a front elevational view thereof;

FIG. 4 is a right side elevational view thereof, the left side being a mirror image;

FIG. 5 is a rear elevational view thereof; and,

FIG. 6 is a bottom plan view thereof.

The details shown in broken lines in FIG. 1 are for illustrative purposes only and form no part of the claimed design.
